UNITED STATES PATENT OFFICE.

ELMER L. KNOEDLER, OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

APPARATUS FOR BURNING AND HARDENING INCANDESCENT MANTLES.

1,172,611.

Specification of Letters Patent.

Patented Feb. 22, 1916.

Application filed September 30, 1913. Serial No. 792,582.

To all whom it may concern:

Be it known that I, ELMER L. KNOEDLER, a citizen of the United States, residing at Gloucester City, Camden county, New Jersey, have invented a new and useful Improvement in Apparatus for Burning and Hardening Incandescent Mantles, of which the following is a full, clear, and exact description, reference being had to the accompanying drawings, forming part of this specification, in which—

Figure 1 is a front elevation of a machine embodying my invention; Fig. 2 is a plan view; Fig. 3 is an end view; Figs. 4 and 5 are detail views, Fig. 4 showing the mantle burned off and ready to be hardened, while Fig. 5 shows the mantle completely hardened; Figs. 4 and 5 also showing the tray or carrier in different positions. Figs. 6 and 20 7 are detail views of a part of the actuating mechanism; Fig. 8 is a plan view of a portion of a tray or carrier; and Fig. 9 is a section on the line IX—IX of Fig. 8.

My invention has relation to apparatus 25 for burning and hardening incandescent mantles; and more particularly to apparatus for use in hardening the mantles in muffles of the character described and claimed in my co-pending application Serial No. 30 749,655, filed February 20, 1913. These muffles are adapted to receive and contain the mantle during the hardening operation, and they are so constructed, as more fully described in my said application, as to permit of the escape of just sufficient of the products of combustion from the hardening burners to form between the inner wall of the muffle and the mantle a resistant cushion of the products of combustion and against 35 which the mantle is shaped and hardened. This intervening cushion of hot gases holds the mantle entirely out of contact with the muffle and enables very complete oxidation 40 to take place in the mantle.

The present invention is designed more especially to provide a machine or apparatus by means of which a plurality of mantles may be simultaneously hardened and shaped in muffles of this character. It is 45 also designed to provide means of simple and convenient character for transferring the mantles from the position in which they are burned to the muffles, and for removing the hardened mantles from the muffles. The

invention also provides means for accurately centering the mantles within the muffles, this being an important feature of the invention. Heretofore, considerable difficulty has been experienced in the centering operation, due to the heating of the guiding elements whereby perfect centering was prevented. My invention overcomes this difficulty by providing guiding means which are so constructed and arranged as not to become heated and which will have a proper centering action at all times.

Other objects and advantages of my invention will hereinafter appear.

Referring to the accompanying drawings, in which I have shown a preferred embodiment of my invention, the numeral 2 designates the frame of the machine, which is provided at its upper rear portion with a burner pipe 3 having a plurality of burners 4 which are used in the preliminary burning 75 operation, as hereinafter described.

5 designates the air supply pipe for the burners 4; and 6 is the gas supply pipe for said burners.

7 designates the series of muffles which are of the character above referred to and more fully described in my said copending application. They conform generally to the contour of the finished mantle, but are of sufficiently greater cross-sectional area so that there is an intervening space left between the mantle and the muffle (as shown in Fig. 5) for the cushion of hot gases against which the mantle is shaped and hardened. The walls of the muffle are perforated, these 80 perforations being of such area as to permit of the retention within the muffle of the proper cushioning of hot gases while permitting the escape of enough of the gases to prevent back pressure within the muffle of 85 a nature to cause the mantles to collapse. These muffles are arranged in series along the front of the machine. In the present instance they are shown as mounted upon a wheeled carriage 8 adapted to be moved back and forth upon a suitable frame or tracks 9. This frame, or tracks, can be raised or lowered by means of a suitable lever 10, so as to properly locate the mantles 90 with reference to the hardening burners 11. A series of these burners is provided, one for 95 each muffle. Each burner is carried by a branch pipe 12 leading from a gas manifold

100

105

13 and having a connection 14 with an air manifold 15. The air manifold is supplied by a pipe 16 at one end of the machine, while the gas manifold is supplied by the pipe 17 at the other end of the machine.

The pipe 16 has a control valve 18, and the pipe 17 has a control valve 19. Each of these valves is normally held closed by a weighted arm 20 attached to the stem of the valve. The valves are automatically opened by means of cams 21 and 22, which are mounted on opposite end portions of a longitudinal shaft 23. This shaft is driven from any suitable source of power. In the drawing, I have shown a countershaft 23^a provided with a belt wheel 24 loosely mounted thereon and having clutch projections 25 adapted to engage a clutch member 26. This member 26 is mounted to rotate with the shaft 23^a, but is capable of a longitudinal movement thereon, and is normally held in clutching engagement with the clutch projections of the wheel 24 by the springs 27.

28 is a yoke connected to the member 26, 25 and carrying a stop pin 29 adapted to be engaged by a pin or projection 30 on a worm wheel 31 mounted on the shaft 23. The wheel 31 is driven by a worm 33 on one end portion of the shaft 23. The pin 29 is mounted in a rocking bearing 34 adapted to be actuated by the link 35 connected to a hand lever 36.

In operation the shaft 23^a will continue to rotate until the pin 30 engages the stop pin 29, and thereby actuates the yoke 28 to release the clutch against the action of the springs 27. During this period, the cams 21, 22 will have held the valves 18 and 19 open. These cams are, however, so timed 40 that when the shaft ceases to rotate their high portions will leave the operating arms 19^a on the valve stems, and the valves will be closed by the action of the counterweights. The shafts 23 and 23^a will remain idle until 45 such time as the hand lever 36 is operated to move the stop pin 29 to the position shown in dotted lines in Fig. 7. The springs will then cause the reengagement of the clutch, and the shaft 23 will again commence to revolve.

It will be seen by reference to Fig. 3 that the cams are so shaped and timed that for a short period of time a small flame is fed into the muffles, which will heat up the refractory supporting rings of the mantles gradually, and thereafter the flame is rapidly increased to blow out the mantle and harden and shape it. In this way the tendency to break the rings is avoided, which 60 would take place to a considerable extent, if short hot flames were suddenly turned on without the preliminary heating up.

During the preliminary burning, and also 65 during the hardening and shaping operations, the mantles are supported by their

lugs 37 on loose plates 38, these plates resting on supports 39 of a tray or carrier 40. (See Figs. 4, 5, 8 and 9.) During the preliminary burning operation, this tray or carrier rests on the upper supporting portion 70 of the frame over the burners 4. As soon as the preliminary burning is completed, the tray is moved forwardly on the supporting portion 2^a, and is then moved to transfer the mantles to the muffles. For this 75 purpose the tray is lowered onto vertical guiding rods 41, which are mounted on the carriage 8. The tray or carrier is provided with holes 42 to receive these guide rods. Preferably one of the holes and guide rods 80 is located at one end of the tray and the other at the central portion thereof, so as to shorten the distance between the two rods and thereby minimize the amount of expansion and contraction in the portion of 85 the tray between them. It is essential for the proper centering of the mantles within the muffles that these holes and rods shall accurately register with each other. As the tray is lowered on these guide rods, the loose 90 plates come to a position of rest on the muffles in the position shown in Fig. 5, and the tray or carrier itself moves down onto the carriage 8 to the position shown in Fig. 4. In this manner the tray or carrier is very 95 largely removed from the action of the burners and is subject to very little expansion and contraction. This insures accurate centering of the mantles in the muffle, no particular care on the part of the operator being 100 required for this purpose. After the hardening and burning operation is completed, the tray or carrier is lifted, thereby lifting the entire series of plates with the mantles suspended therefrom. The muffles may be 105 provided with the spring supports 43, mounted on the frame member 9.

The operation of the apparatus will be understood from the foregoing. A plurality 110 of mantles is given the preliminary burning operation, and without removing them from the tray, the tray is pushed across the portion 2^a of the frame, and with its mantles is then transferred onto the carriage 8 in the manner just described. The operator 115 then moves the carriage underneath the hardening burners, and then actuates the lever 36 to throw the starting clutch into operation. The air and gas valves are thus automatically opened and remain open until 120 the cams 22 cease to act thereon. They are then automatically closed, and the shafts 23 and 23^a come to rest. The operator then lifts the tray to raise the entire series of 125 mantles out of the muffles, and the apparatus is ready for the next operation.

The apparatus is exceedingly simple in its construction and operation, and provides means whereby a plurality of mantles may be simultaneously burned and then simul- 130

aneously hardened and shaped with a minimum of handling and without skilled labor. One adjustment of the gas and air valves controls the supply of air and gas for all the hardening burners; and inasmuch as the gas and air valves are opened and closed automatically, each mantle is treated for the same length of time, thus insuring uniformity of product. This uniformity of product is further obtained by the construction of the muffles, as more fully described in my application above referred to. As a result, I am able to produce mantles in large numbers, each one of which is in all essential respects a duplicate of the others. The mantles being inclosed within the muffles while being hardened are not subject to distorting outside influences such as drafts of air, and the perfection of the product is in no way dependent upon the judgment of the operator.

It will be understood that many changes can be made in the details of construction and arrangement of the parts without departing from the spirit and scope of my invention as defined in the claims. Thus, the preliminary burning may take place on a machine which is structurally independent of the apparatus for hardening and burning; any suitable clutch mechanism and automatic valve-actuating mechanism may be employed; instead of using separate gas and air supply pipes, pressure gas may be employed; and various other changes may be made in the details.

I claim:—

1. In apparatus for hardening and shaping mantles, a series of muffles, supporting means therefor, a holder for a series of mantles, said holder and the muffles being capable of a relative vertical movement, and the holder having openings which will pass the upper portions of the muffles, said holder also having a separate support for each mantle, said supports being movably seated in said openings and each having means for engaging and supporting the ring of a mantle, substantially as described.

2. In apparatus for hardening and shaping mantles, the combination with a group of muffles, and a burner for each muffle, of a holder for a group of mantle supports, and a separate support for each mantle removably mounted on said holder, each of said supports having means for engaging and supporting the ring of a mantle, and each of said supports also having means for separately centering it with respect to its corresponding muffle together with means for seating each support over a muffle independently of said holder, substantially as described.

3. In apparatus for hardening and shaping mantles, the combination with a plurality of separate muffles, of a movable man-

tle carrier having seats for a plurality of separate mantle supports, a plurality of mantle supports adapted to said seats each of said supports having means for engaging and supporting the ring of a mantle, and means whereby each of said supports may be individually centered on its seat with respect to one of the muffles, together with means for seating each support over a muffle independently of said holder, substantially as described.

4. In apparatus for hardening and shaping mantles, a plurality of muffle cavities arranged to receive the mantles, a support or carrier for a plurality of mantles, and separate centering means for each mantle engaging its respective muffle arranged to center the mantles individually within the individual muffle cavities, substantially as described.

5. Apparatus for hardening and shaping mantles, comprising a muffle support, a plurality of muffles on said support, a mantle carrier, and a plurality of mantle holders arranged to be movably seated on said carrier, and the muffle support also having means for seating the mantle holders, substantially as described.

6. Apparatus for shaping and hardening mantles, comprising a muffle support having raised supporting portions, muffles seated on said supporting portions, a mantle carrier having openings adapted to fit over the raised muffle-supporting portions, and separate mantle supports adapted to be seated on said carrier and also to be carried on the muffle supports, substantially as described.

7. Apparatus for hardening and shaping mantles, comprising a series of muffles with in which the hardening and shaping is effected, means for simultaneously raising and lowering a series of mantles into and out of the muffles, and means for simultaneously centering the entire series of mantles, said muffles having means for keeping the mantles out of contact therewith during the hardening and shaping operations; substantially as described.

8. In apparatus for treating gas mantles, a tray or carrier having a plurality of loose mantle-supporting plates; substantially as described.

9. A machine for treating incandescent gas mantles, comprising a tray or carrier having a plurality of vertically movable loose plates thereon, each of said plates having means for supporting a mantle; substantially as described.

10. In apparatus for treating incandescent gas mantles, the combination with a series of muffles in which the mantles are shaped and hardened, of a movable tray or carrier, a plurality of loose plates adapted to be supported on the tray or carrier, and also to be

- supported on the muffles, each of said plates having mantle-supporting means, and means whereby the tray or carrier may be moved away from the plates when the latter are 5 supported by the muffles; substantially as described.
11. In apparatus of the character described, the combination with a series of hardening burners, of a carriage movable 10 transversely with respect to the burners, and a plurality of muffles mounted on said carriage, together with means for simultaneously inserting and removing mantles from all the muffles; substantially as described.
12. In apparatus for hardening and shaping mantles, a muffle support, a plurality of muffle cavities, a support for a plurality of mantles, said supports being movable relative to each other, and coöperating guiding and centering means upon the muffle support and the mantle support, respectively, arranged to engage each other during the relative movement of said supports, substantially as described.
13. In apparatus for hardening and shaping incandescent mantles, a support for a plurality of mantles, having a separate loose support thereon for each mantle, a muffle support, and muffles having means co-operating with the loose plates for centering each mantle in its individual muffle cavity, substantially as described.
14. In apparatus for hardening and shaping mantles, a support for a plurality of muffles, a support for a plurality of mantles, and a separate support loose on the general mantle support for carrying each mantle, 30 said individual mantle supports being movable vertically relative to the general mantle support during movement of the mantles and muffles relative to each other, substantially as described.
15. In apparatus for hardening and shaping mantles, a series of burners, a carrier having a series of muffle cavities, said carrier being movable into and out of the vertical 40 plane of the burners, and said burners and muffles being capable of relative movement toward and from each other, substantially as described.

16. In apparatus for hardening and shaping mantles, a series of burners, a support carrying a series of muffle cavities, and a mantle support, the mantle support and the muffle support being movable into and out of the vertical plane of the burners, substantially as described.

17. In apparatus for hardening and shaping mantles, the combination of a muffle support, a plurality of muffles carried thereby, a mantle carrier having openings arranged to fit over the upper portions of the muffles, and a plurality of mantle supports on said carrier and adapted to be loosely supported on the mantle carrier and also on the muffle support, substantially as described.

18. In apparatus for hardening and shaping mantles, a support for a series of burners, a support for a series of muffle cavities, and a mantle carrier arranged to be positioned on the muffle support, substantially as described.

19. In apparatus for hardening and shaping mantles, the combination of a muffle support, a plurality of muffles carried thereby, a mantle carrier having openings arranged to fit over the upper portions of the muffles, and a plurality of mantle supports on said carrier and adapted to be loosely supported on the mantle carrier and also on the muffle support, together with means whereby each of the mantle supports is separately centered with respect to a corresponding muffle when such mantle support is seated on the muffle support, substantially as described.

20. In apparatus for hardening and shaping mantles, a series of burners, a series of muffles, a support for a series of mantles, 90 connections for furnishing fuel to the burners, and automatic mechanism arranged to automatically turn on a relatively small proportion of fuel to give a heating up flame, and thereafter increase the amount of fuel 95 to give the full hardening and shaping flame, substantially as described.

In testimony whereof, I have hereunto set my hand.

ELMER L. KNOEDLER.
